UNITED STATES PATENT OFFICE.

DANIEL BAKER DIMICK, OF BIRMINGHAM, ALABAMA.

MOLDING OF SPIRAL CORRUGATED CAST-IRON PIPE.

Application filed November 10, 1924. Serial No. 749,068.

To all whom it may concern:

Be it known that I, DANIEL BAKER DIMICK, a citizen of the United States, residing at Birmingham, in the county of Jefferson and State of Alabama, have invented certain new and useful Improvements in Molding of Spiral Corrugated Cast-Iron Pipe; and I do hereby declare the following to be a full, clear, and exact description of the invention, such as will enable others skilled in the art to which it appertains to make and use the same.

The present invention relates to improvements in apparatus for casting pipe and relates more particularly to the production of seamless, spirally corrugated cylindrical pipe of the kind shown and described in my co-pending application entitled Cast pipe and joint therefor, filed September 16, 1922, Serial No. 588,650.

A previous machine for the casting of pipe of this character is shown and described in a second copending application, Serial No. 588,649, filed September 16, 1922.

According to this previous machine the hollow, spirally corrugated pattern, after forming the mold cavity, is itself simultaneously rotated and lifted axially of the mold whereby to withdraw the pattern from the cavity.

In accordance with the present invention the pattern is simply lifted axially, while held against rotation, during rotary movement of the mold; and consequently it is the purpose of the present invention to dispense with the more complicated mechanism included in the previous machine for imposing a simultaneous rotary and axial movement upon the pattern in favor of a simplified construction in which the pattern is made non-rotatable and capable of axial movement, the axial movement being accomplished by the simple rotation of the mold aided by counterweights and possibly by the hand of the operator.

A further object of the present invention is to provide for the efficient foundry handling of the patterns and molds and in so grouping units of the mechanism as to economize on floor space in the foundry and upon the number of operators required to attend a given number of the machines.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation, with parts in section of the improved machine.

Figure 2 is a vertical section taken through the machine showing the pattern and other parts in a subsequent position.

Figure 3 is a top plan view of the machine.

Figure 4 is a section taken on the line 4-4 in Figure 2 with the arm swung toward the side, and

Figure 5 is a diagrammatic view showing the grouping of machines on the foundry floor.

Referring for the present to Figures 1 to 4 inclusive 6 designates the cylindrical, hollow, spirally corrugated pattern suspended from the outer end of the arm 7 which is permitted to slide vertically upon the post 8 but prevented from rotating relatively to the post by reason of the engagement of the key 9 in the vertical groove 10 of the post.

The post, however, is itself free to rotate about a substantially vertical axis and for this purpose it is mounted in the cylindrical pedestal 11 having the perforated flanges 12 at its base by which it is secured to the base plate or bed 13, the base plate being in turn bolted or otherwise affixed to the floor or foundation. Anti-friction bearings 14 are interposed beneath the lower end of the post 8 to afford easy rotation as by the hand of the operator. The arm 7 forms a lever by which the post and pattern may be swung. Figures 3 and 4 are comparative views showing the two positions of the arm. When the pattern is in the position over the mold a plug or pin 15 may be inserted through the pedestal and into a socket in the post 8 for holding the parts against accidental rotation. A dust collar 16 is secured to the post just above the upper end of the pedestal to exclude foreign matter from the bearings.

The arm 7 is preferably counter balanced to aid in the vertical movement, as when the pattern is raised and lowered. For this purpose a cap 17 is placed over the upper end of the post. From the cap extends a pair of forward arms 18 and a pair of rear arms 19, the arms each carrying pulleys or rollers 20 and 21. Four such pulleys are shown in Figure 3, the front pulleys being in line with the rear pulleys so as to receive the two cables 22 and 23 cou-

pled to the arm 7 and to eye bolts 24 sustaining the counter weight 25.

The cables may be wrapped one or more times about the pulleys. In practice it is found best to simply have the cables play up and over the front pulleys and to be wrapped once about the rear pulleys. The counter balance weights 25 may be added to or reduced.

10 As shown in Figure 1 an endless hand cable or strap 26 extends down from a wheel 27 mounted upon the shaft 28 upon the cap plate. This shaft carries a pinion 29 meshing with a gear wheel 30 on the rear pulley 15 shaft 31. By drawing upon either run of the cable 26 the operator may aid the vertical movement of the pattern.

The outer end of the arm carries an integral or attached ring 32 adapted to receive the ring 33 of the coupling head 34, bolts or other fastenings 35 being employed to detachably hold the rings together. The drawing head is provided with external and internal spaced flanges 36 and 37 to receive the upper ring 38 of the pattern 6. Pins 39 passing through the flanges 36 and 37 and the ring 38 are used to suspend the pattern from the head. This arrangement provides for flexibility in the pattern 30 to enable the pattern to accommodate itself to the mold and to the cavity in screwing out of the mold.

As shown in Figure 1 the pattern 6 is adapted initially to fit down within the mold composed of the cheek 40 and the core arbor 41. Both the cheek and arbor are pinned or otherwise affixed to the casting stool 42 as indicated respectively at 43 and 44. The mold parts are thus preserved in 40 proper spaced relation and at the same time caused to turn with the casting stool 42. The casting stool 6 rests upon the turn table 44 to which it is secured as by the pins 45.

The pattern 6, when in the mold, as appears in Figure 1 fits substantially midway between the cheek and the core and a sand-slinger is employed to throw sand upon both sides of the cylindrical pattern 6 making, in one molding operation a spiral, continuously cylindrical cavity 46 in the sand having external and internal walls upon which the spiral corrugation is simultaneously formed, the corrugations upon the inner wall being in lead with those upon the outer wall.

The stripping plate is designated at 47 and is made up in two half sections so that it may be put in place upon the upper end of the cheek 40 after the sand has been introduced. The interior wall of the stripping plate is corrugated to conform to the external corrugations of the pattern 6 and to fit the outer wall of the pattern snugly. This stripping plate is pinned or clamped to the upper end of the cheek. Figure 2 shows

the pattern withdrawn leaving the spiral cavity in the mold and the stripping plate in place upon the top of the cheek.

The turn table 44 is mounted upon the shaft 48 having the upper tapered portion 49 fitting in the upper tapered bearing 50 provided with the removable cap plate or box 51. The lower portion of the shaft 48 fits within a cylindrical bearing 52 and upon anti-friction bearings 53 in the base 75 thereof while a dust collar 54 is secured upon the shaft just above the lower cylindrical bearing 62. It is obvious that the turn table might be supported in any other manner appropriate to sustain the weight 80 of the mold and other parts while permitting of free rotation thereof.

An internal gear 55 is made upon the lower portion of the turn table 44. A pinion 56 meshes with the internal gear, the 85 pinion being driven by the electric motor 57 through an appropriate reduction gear 58 having the high speed shaft 59 and the lower speed shaft 60. Any other motor might be used and appropriate control 90 means is connected to the motor.

The apparatus might, for purposes of understanding the diagrammatic illustration in Figure 5, be divided up into two parts, one called the centering machine consisting 95 of the rotatable post 8 and its supporting arm 7 by which the pattern 6 is brought to a correct position with respect to the empty flask, and the second machine is the 100 turning machine or turn table consisting of the assembly for supporting and imparting to the flask a rotary movement to effect removal of the pattern 6 from the sand cavity.

In Figure 5 the centering machines are 105 designated "C. M." and it will be seen that three of these centering machines are employed located in triangular arrangement. Each centering machine serves two turn tables driven by the independent motors designated at "M".

These turn tables are all located on the arc of a circle struck from a center where the sand-slinger is located so that the sand-slinger has a radius of activity covering all of the tables. One sand-slinger is therefore easily enabled to take care of the six flasks upon the turn tables. The sand-bin and conveyors are also indicated in this diagrammatic view at the open side of the circle for supplying sand continuously to the sand-slinger.

While the sand-slinger is packing sand in a flask upon one turn table of each pair, the centering machine is engaged in placing a pattern in the empty flask of the companion turn table so that the operation is substantially a continuous one and three centering machines and a single sand-slinger are enabled to take care of six turn tables.

After the flasks have been rammed and the patterns 6 removed, the flasks are withdrawn to the casting floor where the molten metal is poured in the spiral cavity.

- 5 In the use of the device a pattern 6 is coupled to the arm 7 and the column 8 is rotated until the pattern is centered above the empty flask upon one of the turn tables. The plug 15 is then inserted in order to 10 prevent possible angular movement of the column 8 and the arm 7 is lowered until the pattern rests upon the casting stool.

The sand-slinger is then put into operation and sand is rammed onto both sides 15 of the pattern 6. Subsequently the turn table 44 is caused to rotate by closing the circuit of the electric motor 57 and inasmuch as the pattern 6 is held fast against rotation the stripping plate will act as a 20 revolving nut tending to lift the pattern out of the sand.

This movement is made easy by the use 25 of the counter weight and also if necessary by the aid of the operator who may pull down upon the counter weight or press up on the arm 7. This pressure should be light in order that the spiral wall in the sand be not distorted.

The pattern is then swung to the other 30 turn table and inserted in the flask and sand is rammed in this flask while the finished flask is removed to the casting floor and an empty flask substituted in its place. The device and the assembly of these devices 35 in the foundry are effected with a view to simplicity in construction and a minimum number of the machines without sacrificing the capacity of the plant. The arrangement shown in Figure 5 makes it possible to operate 40 the plant with considerably less labor.

It is obvious that various changes and modifications may be made in the details of construction and design of the above specifically described embodiment of this invention without departing from the spirit thereof, such changes and modifications being restricted only by the scope of the following claims.

What is claimed is:—

50 1. An apparatus for casting pipe comprising a rotary turn table, means to rotate said turn table, a flask supported upon said turn table, and a spiral pattern held against rotation and supported for axial movement of the pattern.

2. An apparatus for casting pipe comprising a spirally corrugated pattern, means for supporting said pattern for substantially axial movement while holding said pattern 60 against rotation, a flask for receiving said pattern and having spaces for sand both upon the exterior and interior of said spirally corrugated pattern, and means for supporting and rotating said flask to cause 65 withdrawal of the pattern.

3. An apparatus for casting pipe comprising a rotary turn table, means for rotating said turn table, a flask adapted to fit upon said turn table, means for causing rotation of the flask with the turn table, a spirally 70 corrugated pattern adapted to fit within said flask, and means for holding said pattern against rotation while permitting it to enter and leave the flask in a substantially vertical direction. 75

4. An apparatus for casting pipe comprising a rotary column, an arm adapted to slide longitudinally on the column but held against relative rotation thereon, a spirally corrugated pattern carried fixedly by said 80 arm, a flask for receiving said pattern, and means for rotating and supporting said flask.

5. An apparatus for casting pipe comprising a column, a support for mounting the 85 column, for swinging movement, an arm slideable longitudinally on said column and turning with the column, counter weight means carried by said column and coupled to said arm, a spirally corrugated pattern 90 held fixedly by said arm, a flask adapted to receive said pattern, and means for rotating and supporting said flask.

6. An apparatus for casting pipe comprising a pedestal, a column supported for rotary movement therein, an arm keyed for slideable movement up and down on said column but fixed against rotation thereon, a spirally corrugated pattern held fixedly on 95 said arm, a counter weight suspended from said column and coupled to said arm, a flask for receiving said pattern, a turn table for fixedly receiving said flask, and a motor for driving said turn table. 100

7. An apparatus for casting pipe comprising a rotary column, an arm slideable on said column and fixed to rotate therewith, a spirally corrugated pattern held by said arm against axial turning movement, a cap upon 110 said column having pulleys thereon, cables running over said pulleys and connected at one side to said arm, a counter weight connected at the other side to said cables, a flask for receiving said pattern and means for supporting and rotating said flask. 115

8. An apparatus for casting pipe comprising a rotary column, an arm mounted for longitudinal movement on said column and secured to rotate therewith, a spirally corrugated pattern held fixedly on said arm, a cap upon said column, pairs of spaced pulleys on said cap, pairs of cables trained over said pulleys, said cables at one side of the column being connected at spaced points to said arm, a counter weight at the other side of said column coupled at spaced points to the other ends of the cables, a flask for receiving said pattern, and rotary means for supporting said pattern. 120

9. An apparatus for casting pipe comprising 130

ing a rotary column, means to hold the column against rotation, a counter weighted arm slideable on said column and rotating therewith, a spirally corrugated pattern supported fixedly from said arm, a flask for receiving said pattern, and a rotary turn table for fixedly supporting said flask.

10. An apparatus for casting pipe comprising a spirally corrugated pattern, means for supporting said pattern for axial movement while restricting the same against rotation, a flask for receiving said pattern, a turn table for supporting said flask having means for cooperating with the flask to cause rotation thereof with the turn table.

a motor for driving said turn table, and a reduction gear between said motor and turn table.

11. An apparatus for casting pipe comprising a turn table, a shaft for supporting said turn table, bearings for said shaft, an internal gear upon the said turn table, a pinion meshing with said internal gear, a reduction gear coupled to said last mentioned gear, a motor for driving said first mentioned gear through said reduction gear, a flask supported upon said table and fixed to rotate therewith, and an axially movable pattern adapted to enter said flask.

DANIEL BAKER DIMICK.
